UNITED STATES PATENT OFFICE.

GEORGE E. SHERWIN, OF MILWAUKEE, WISCONSIN.

CLOTHESLINE REEL.

Application filed April 25, 1922. Serial No. 556,361.

To all whom it may concern:

Be it known that I, GEORGE E. SHERWIN, a citizen of the United States, and resident of Milwaukee, in the county of Milwaukee, 5 and State of Wisconsin, have invented certain new and useful Improvements in Clothesline Reels; and I do hereby declare that the following is a full, clear, and exact description thereof:

10 The invention relates to clothes-line reels. It comprises a cup shaped receptacle having an opening in its side thru which a clothesline may run and a pair of openings receiving the ends of a loop serving as a handle. A 15 wire is provided with a loop to which the line is secured, and has bearings in a flat wall of the container and in a lid which has a slip fit with the container, and is provided with radial deformations adapted to cooperate with a portion of the wire to limit the 20 rotary movement of the wire, which may be wound by means of a crank formed therein, carrying a knob. The clothes-line is provided with a series of rings threaded thereon, 25 and is secured to a snap fastener carrying an end ring.

A primary object of the invention is the extreme convenience of use of the device. The clothes-line is readily strung up, the end ring being affixed to a suitable hook and the 30 other rings threaded over other hooks, the line being tensioned readily in the rings. The clothes-line is unwound quickly, the unwinding necessitating merely a movement 35 of the reel receptacle. Inasmuch as only so much of the line is unwound as is needed, there is no tangling. In taking down the line, it may be wound rapidly on the reel, this calling for a mere turning of the handle, 40 and when completely wound, the entire device takes up a very small amount of room.

A very important object of the invention is economy of manufacture. The reel container is similar to a tin can. The lid has a 45 slip fit connection therewith, so that there is no complication of parts in securing the lid to the container. The reel is a mere wire, which is looped so that the end of the line may be readily secured and the container itself provides bearings for the wire. A mere looping of the wire limits the movement thereof in one direction by contact of the loop with the container, and a similar 50 loop cooperates with deformations in the lid to retard the rotation of the wire. The retarding means is therefore quite simple. The

handle is merely a bent piece of wire and it is secured to the container by the mere provision of a pair of spaced apertures. The apertures serve, therefore, to securely retain 60 the handle and at the same time, permit it pivotal movement so that it may be swung in close to the container to take up less room.

With the above and other objects in view 65 which will appear as the description proceeds, the invention resides in the novel construction, combination and arrangement of parts substantially as hereinafter described and more particularly defined by the ap- 70 pended claims, it being understood that such changes in the precise embodiment of the herein disclosed invention may be made as come within the scope of the claims.

In the accompanying drawing, is illus- 75 trated one complete example of the physical embodiment of the present invention constructed according to the best mode so far devised for the practical application of the principles thereof, and in which:

Figure 1 is a central section thru an embodiment of my invention.

Figure 2 is a transverse section thereof on the line 2—2 of Figure 1, and

Figure 3 is a side elevation of the invention.

The container comprises a cup shaped portion having a cylindrical side wall 10 cut away to provide an opening 11, the metal being bent back to form beads 12 to prevent 90 cutting of the line. A handle 13 is secured to side wall 10 by means of ends 14 laterally deflected and received in openings in the side wall, the metal between the openings being slightly deformed. Thus the handle 13 is securely retained in position and permitted pivotal movement, whereby it may 95 be swung in close to the side wall 10. A flat rear wall 15 is secured to side wall 10, by means of peripheral flange 16. Wire 17 100 operates as a reel, and is formed into a loop 18 to which the line 19 is secured. The wire is also formed into relatively elongated loops 20 and 21, loop 20 being immediately adjacent end 22 directed thru an opening in wall 15. Thus loop 20 operates to limit the movement of wire 17 with respect to wall 15.

Lid 23 is provided with a narrow peripheral flange 24, adapted to contact with a reinforcement 25 U shaped in cross section, 110 gripping the edge of side wall 10. The lid terminates in a lateral bead 26, adapted to

fit snugly against reinforcement 25. The lid is provided with a series of radial deformations 27, inwardly directed and adapted to cooperate with loop 21, the wire 5 17 being directed thru an opening in the lid and deflected to form a crank 28 carrying a knob 29. The clothes-line 19 is secured to an eye 30 of a snap fastener 31, which carries a ring 32. The ring may be removed 10 from the snap fastener and any number of similar rings 33 may be positioned on the line.

In stringing up, the ring 32 is placed over a hook, or other retaining means, and 15 the line is drawn towards other retaining means over which a ring 33 may be positioned and from this retaining means, the line may be extended to another retaining means and secured thereto readily by means 20 of another ring 33. Thus these rings provide a very ready means of stringing up the line. They further permit the ready tensioning of the line 19. The line is automatically unreeled by merely drawing the 25 container away, the container being carried manually by handle 13.

After as much of the line is unwound as is desired, the container may be positioned at any convenient place and the retaining 30 deformations 27 cooperate with loop 21 to prevent accidental unwinding of the line. Thus there is no possibility of tangling. The parts of the container may be readily assembled and operated the assembly calling 35 merely for the insertion of end 22 in an opening of side 15 and the slipping of lid 23 into position.

I claim:

1. In a clothes-line reel the combination 40 of a cup-shaped container having an opening in the end wall, a closure member forming

ing a second end wall having a second opening therein and a winding wire extending through said opening, said wire having a pair of laterally directed deformations, one 45 of said deformations being inwardly of and adjacent to said first mentioned opening, the other of said deformations being inwardly of and adjacent to said second opening.

2. In a clothes line reel the combination of a cylindrical container, a flat end wall on said container having an opening therein, a lid serving as a second end wall for said container and having a second opening therein 55 and a winding wire extending through said openings and formed into a radially directed loop adjacent said first mentioned opening, a second radially directed loop adjacent said second opening and a third loop 60 intermediate of said first and second loops.

3. In a clothes-line reel, a cup like receptacle having a cylindrical side wall with an opening therein, a flat side wall having an aperture therein, a lid having an 65 aperture therein, a wire having an end projecting thru said first mentioned aperture, and a relatively elongated loop contacting with said flat side wall, a central loop formed in said wire, a clothes-line 70 secured to said central loop, a third loop formed in said wire, said wire extending thru an opening in said lid, said lid having a series of radial depressions therein co-operating with said third loop to retard the 75 movement thereof, and a crank on said wire for rotating said wire.

In testimony that I claim the foregoing I have hereunto set my hand at Milwaukee, in the county of Milwaukee and State of 80 Wisconsin.

GEORGE E. SHERWIN.
